UNITED STATES PATENT OFFICE.

THOMAS R. GRIFFITH, OF NEW SOUTHGATE, LONDON, ENGLAND, ASSIGNOR TO WESTERN ELECTRIC COMPANY, INCORPORATED, OF NEW YORK, N. Y., A CORPORATION OF NEW YORK.

METHOD OF AND APPARATUS FOR BENDING FILAMENTS.

Application filed October 10, 1924. Serial No. 742,756.

This invention relates to a method and apparatus for bending and forming refractory material and particularly refractory filaments such as are used in high power electron discharge devices.

It has for an object to facilitate the transformation of a long length of refractory wire into a desirable form, such as M-shaped or V-shaped filaments for the above purpose.

This object is attained by providing a metallic standard having a hand operated plunger which insulatingly supports a plurality of electrode jaws and a bending frame which carries a measuring yoke and a removable insulating plate. A filament wire is laid in a slot in the insulating plate and the plunger lowered until it contacts with the filament wire, whereupon a circuit is established between the electrode jaws and the portion of the wire between the jaws is heated and bent over the insulating plate. The bent filament wire is removed from the frame and the bent portion placed over the hook on the measuring yoke, the parallel strands of the wire being laid in the slots of the insulating plate and the plunger again lowered to bend the wire to form the filament in the desired shape in which it will be used in an electron discharge device. A filament formed in this manner can be attached to the filament supporting structure in the device without any "truing up" or measurements of the length of the strands between bends.

Referring to the drawings:

Figure 1 is a side view of the bending jig made in accordance with this invention.

Fig. 2 is an enlarged sectional front view 40 with the filament wire held in position.

Fig. 3 is the same as Fig. 2 but showing the plunger in its operated position.

Fig. 4 is an enlarged plan view of a section of the jig illustrating the second 45 step of the bending operation.

Fig. 5 is a front view of Fig. 4 showing the bent filament in dotted lines, and

Fig. 6 is the complete bent filament ready 50 to be inserted in a high power electron discharge device.

Referring to Fig. 1, the bending jig comprises a metallic standard 1 provided with an apertured extension bent at right angles

to the standard through which bolts are passed to fasten the standard to a base or work bench 2. An apertured metallic block 3 is fastened to the standard 1 adjacent the upper end thereof and forms a guiding member for the plunger rod 4, which is attached to the hand operated lever 5 carried at the upper end of the standard 1. A slot 6 is provided on one longitudinal surface of the plunger rod 4 and a set screw 7, fastened through the guide member 3, limits the upward and downward movement of the plunger rod 4. An integral bifurcated extension 8 on the lower end of the plunger 4 is provided with apertures to receive a locking screw to support an insulating block 9, preferably of "lavite". The insulating block 9 is of such formation as to provide a rigid continuation of the plunger 4 and insulatingly supports metallic electrodes 10 and 11 which are carried at the lower end of the insulating block 9. The electrodes 10 and 11 are supported from the block 9 by means of a screw 12 passing through the electrodes and the insulating block 9. The electrode 10 is insulated from electrode 11 by having a larger bore through which the screw 12 passes and being insulated from the screw 12 by insulating washer 13. Suitable electrical connections 14 and 15 are attached to the electrodes and connected to any desirable source of power. The contacting surfaces of the electrodes 10 and 11 are curved inwardly to prevent the electrodes cutting the filament wire in the bending operation to be described hereinafter.

A rectangular metallic frame 16 having an extension 17 bent at right angles to the plane surface of the frame is arranged in an edgewise position with respect to the plunger rod 4 and attached to the frame by means of bolts and nuts. The frame 16 is positioned on the standard in such a manner that when the plunger is lowered the electrodes 10 and 11 pass on either side of the edge of the frame 16. A portion of the frame is cut away to provide a seat for insulating plate 18, which is preferably of "lavite," the plate being provided with a rounded edge having indentations 19. A pair of metallic guiding strips 20 are attached to the frame on one side of the cut portion, the upper ends

of the strips projecting above the edge of the frame and one side of the guiding strip projecting over the edge of the cut portion of the frame. A pair of similar guiding strips 21 are attached to the frame on the opposite side of the cut portion and together with the strips 20 form a pocket for the insulating plate 18. This construction provides suitable means for replacing the insulating plate 18 in the event of breakage or renewing the plate after continued use. Attached to the frame 16 on the outer edge of the guiding strips 20 and 21 are stationary bearings 22 and 23 through which pins 24 and 25 extend to carry movable bearings 26 and 27. The movable bearings 26 and 27 are provided with apertured extensions 28 and 29 to which is attached a measuring yoke 30 by means of rivets. A hook member 31 projects from the upper surface of the yoke 30 and is positioned near the converging point of the arms of the yoke. The normal position of the yoke is generally in a substantially parallel plane with the frame 16 but in its operated position is swung up at right angles to the frame and lies in a plane substantially the same as the edge of the frame. This arrangement provides a jig which may be used for bending both V and M shaped filaments since the loosely pinioned yoke is only used when the M shaped filament is desired.

The operation of the bending jig will now be described. A filament wire A, of refractory material, such as tungsten, of suitable length to form a filament, is laid across the bending frame 16 and positioned in one of the slots 19 in the insulating plate 18. The lever 5 is operated, whereby the plunger 40 is lowered and the electrode jaws 10 and 11 contact with the filament wire A. This operation establishes a metallic circuit through the electrode jaw 10, a portion of the filament wire and electrode jaw 11, whereby the portion of the filament wire between the electrode jaws is heated to a red glow and pressure is then applied to the plunger to bend the filament wire over the frame to complete the first operation. The filament wire is removed from the frame and comprises two strands B and C in substantially parallel relation. The bent portion of the filament wire is hooked over the pin 31 in the measuring yoke 30 and the yoke swung up to a plane approximately the same as the edge of the bending frame, and the strands B and C laid in the slots 19 in the insulating plate 18. The plunger is again lowered until the electrodes contact with the strands B and C and a circuit established to heat the portions of the strands between the electrode jaws. The plunger is further operated to bend the filament wire over the frame and the plunger withdrawn to remove the filament wire from the bend.

ing frame. The filament wire now comprises four strands, B, C, D and E, as shown in Fig. 6, and is formed into the desired shape in which it will be used in a high power electron discharge device.

Although this invention has been described with reference to the bending and forming of a highly refractory metal filament it is within the scope of the invention to bend other forms of refractory metal and other metals in wire form in which it is desired to electrically heat and bend portions of the wire to form desirable shapes and configurations.

What is claimed is:

1. A filament forming apparatus comprising a standard, a movable plunger attached to said standard, a plurality of electrodes carried by said plunger, a frame attached to said standard, a removable grooved insulating plate carried by said frame, and a yoke loosely mounted on said frame for holding the filament in adjusted position on said plate.

2. A filament bending device comprising a standard, a lever attached to said standard, a plunger carried by said lever, guiding means for said plunger attached to said standard, an insulating block supported by said plunger, a plurality of electrodes carried by said insulating block, a metal frame arranged edgewise with respect to said plunger and attached to said standard, a removable insulating plate, means on said frame to support said plate, and a swinging yoke carried by said frame.

3. A filament bending device comprising a standard, a frame attached to said standard intermediate the ends thereof, an insulating plate positioned in said frame, retaining means for said plate attached to said frame, bearings carried by said frame, a swinging yoke supported from said bearings, a guide block attached to said standard, a plunger slidably mounted in said block, means for operating said plunger, and a plurality of metallic electrodes insulating supported by said plunger.

4. A filament bending device comprising a standard, a bending frame attached to said standard, an insulating plate carried by said frame, said plate being adapted to receive a filament wire to be bent, a slidable plunger carried by said standard, an insulating block carried by said plunger, and a plurality of electrodes supported by said block, whereby the contact of said electrodes on said wire completes a circuit to heat a portion of said wire and bend said wire over said plate.

5. A filament bending device comprising a standard, a bending frame attached to said standard, an insulating plate carried by said frame, said plate adapted to receive a filament wire to be bent, a swinging yoke

supported at either side of said plate, a pin carried by said yoke, said pin being adapted to carry the filament wire, said yoke being swung in the same plane as the edge of said insulating plate, the parallel strands of the filament being laid on said insulating plate, and a slideable plunger carried by said standard and adapted to apply pressure to the filament wire whereby the filament wire is bent in the form in which it will be used in vacuum tubes.

6. The method of bending and forming a refractory wire which comprises laying said wire on a bending frame having a swinging yoke, lowering a plurality of electrodes in contact with said wire, applying pressure to portions of said wire to bend said wire over said frame, removing the bent wire from the frame, attaching the bent portion to said yoke, elevating said yoke to the plane of the edge of the frame, positioning the two strands of the bent wire across said frame, and thereafter lowering the elec-

trodes on said strands to bend said strands over said frame.

7. A bending device comprising a standard, a frame attached to said standard, said frame having a removable insulating plate to receive a wire to be bent, a plunger mounted on said standard, a plurality of electrodes carried by said plunger cooperating with said plate and a movable yoke for positioning said wire on said plate.

8. A bending device comprising a standard, a frame attached to said standard, said frame being adapted to receive a wire to be bent, a plunger carried by said standard, a plurality of electrodes supported by said plunger and adapted to heat and bend the wire over said frame, said electrodes passing on either side of said frame.

In witness whereof, I hereunto subscribe my name this 25th day of September, A. D. 1924.

THOMAS R. GRIFFITH.
